United States Patent Office

Des. 180,624
Patented July 9, 1957

180,624

FINGER RING SPIRIT LEVEL

Edward W. Souter, Moss Beach, Calif.

Application November 13, 1956, Serial No. 43,744

Term of patent 14 years

(Cl. D45—10)

Fig. 1.

Fig. 2.

Fig. 3.

Fig. 4.

Fig. 1 is a perspective view of a finger ring spirit level embodying my new design;

Fig. 2 is a top plan view of the same;

Fig. 3 is an end view of the same; and

Fig. 4 is a front elevation of the same.

I claim:

The ornamental design for a finger ring spirit level, substantially as shown.
